UNITED STATES PATENT OFFICE.

EDWARD B. VERNEUIL, OF MANGUM, OKLAHOMA.

OIL-WELL STRAINER.

Application filed October 25, 1922. Serial No. 596,824.

To all whom it may concern:

Be it known that I, EDWARD B. VERNEUIL, a citizen of the United States, residing at Mangum, in the county of Greer and State 5 of Oklahoma, have invented new and useful Improvements in Oil-Well Strainers, of which the following is a specification.

My present invention has reference to a strainer for oil wells, and has for its object 10 to produce a strainer for this purpose made up of any desired number of sections of apertured tubular members having a heavy coating of Monel metal to render the same acid-proof and non-corrosive, in combination 15 with tubular mineralized animal and vegetable fiber woven cloth which is acid resisting to strain the fine sand, which in the coastal field is commonly known as beach sand, the tubular fiber being enclosed in a 20 comparatively finely reticulated tube which is also coated with heavy Monel metal or other acid and rust-proof metal, and as a consequence to produce a strainer which shall be long lived, in which the liability of 25 rust erosion from the action of salt water is overcome and the collapse of the device is thus effectively prevented.

To the attainment of the foregoing and other objects which will present themselves 30 as the nature of the invention is better understood, reference is to be had to the drawings which accompany and which form part of this application.

In the drawings:

35 Figure 1 is a side elevation of the improvement.

Figure 2 is a sectional view on the line 2—2 of Figure 1.

40 Figure 3 is a sectional view on the line 3—3 of Figure 1.

Figure 4 is a fragmentary perspective view of the heavy tube employed.

Figure 5 is a similar view of the corrugated and reticulated tube employed.

45 Figure 6 is a view similar to Figure 2, but illustrating a modification.

Figure 7 is a sectional view on the line 7—7 of Figure 6.

As disclosed by the drawings I make use 50 of any desired number of heavy iron tubes 1, each of which having its upper end provided with a hub 2 and a flange 3 projecting inwardly of the hub to provide therewith a pocket for the straight end of the 55 next connected tube. Each tube is provided with comparatively large openings 4, the

same being arranged in vertical series and in staggered relation with respect to each other. The tubes 1 have a heavy coating of Monel metal to render the same acid-proof or non- 60 corrosive.

In one form of the invention I arrange upon the exterior of the tubes 1 tubular mineralized animal or vegetable fiber woven cloth 5 treated to render the same acid-resisting and designed to prevent the fine sand entering the openings 4 in the tubes 1. Around the fiber tubes 5 I arrange comparatively heavy and also comparatively closely apertured tubes 6. These tubes may be provided, as shown in certain figures of the drawings, with preferably equi-distantly spaced annularly disposed outwardly bulged portions 7 designed to catch the sand before the same contacts with the fiber tubes 5, and also designed to serve as pockets for the sand which enters the said bulged or corrugated portions. The tubes 6 are heavily coated with Monel metal or any other acid and rust-proof metal so that the strainer 70 will not be affected by salt water or other agents that cause the collapse of strainers of this character. The fiber tubes 5 provide a filtering medium for the tubes 1 and 6 as well as a packing for the said metal tubes. 75

I may find it desirable to remove the fiber tubes 5, and the outer tubes 6 for the cleaning of the same, and therefore I have illustrated in certain figures of the drawings connected tubes 8 similar to the tubes 1, and 80 have arranged therein a pair of spaced tubes 9 and 10 similar to the tubes 6. These tubes may have their lower ends connected together and preferably threadedly engage the tubes 8. Between the tubes 9 and 10 there 85 are fabric tubes 11 similar to the fabric tubes 6.

The tubes 9 and 10 being connected together, and being threadedly engaged with the tubes 8 permit of the removal of the 90 strainer tubes 9 and 10 and the fiber packing between the tubes so that these elements may be cleaned and replaced, when desired. Of course, a suitable tool is employed for connecting the tubes 9 and 10 to the tube 8 and for removing and lifting the same from the said tube 8, but as any desired means may be employed for this purpose, I have not deemed it necessary to illustrate the same. 95

It is thought that the foregoing description, when taken in connection with the drawings will fully set forth the construc- 100 105 110

tion and advantages of my improvement to those skilled in the art to which this invention relates, so that further detailed description will not be required.

Having described the invention, I claim:—

An oil well strainer constructed of heavy iron tube sections which are coated with an acid-resisting substance and having spaced 10 openings therethrough, each of said tubes having a hub at one end receiving the end of the next tube thereon for connecting the tubular sections, other apertured tube sec-

tions surrounding the first mentioned section and held thereon by the confronting base and mouth of the hubs of said first mentioned tube sections and woven fiber tubes of acid-resisting material arranged between the joints of the first mentioned tube sections and the metal tubes on said sections, and said fiber tubes providing a packing as well as filtering medium for said inner and outer metal tube sections.

In testimony whereof I affix my signature.

EDWARD B. VERNEUIL.
